PACKAGE VENDING MACHINE

Jacob H. Rubenstein, Syracuse, N. Y.

Application October 30, 1947, Serial No. 783,082

7 Claims. (Cl. 312—63)

1

This invention relates to package vending machines, as for example machines for vending packages of cigarettes. It is desirable that such machines be so constructed that the packages are vended, or made available, to the purchaser at a point substantially waist high from the floor. The most practical manner in which to arrange the packages for vending is to arrange them in stack or column formation above the package ejecting mechanism, whereby the packages are fed to the mechanism by gravity. With such an arrangement, the supply of packages must be confined between the discharge mouth, or opening of the machine, and the top of the cabinet.

Vending machines of this type are located in places frequented by the public in relatively large numbers, such as theatre lobbies, building corridors, etc., and in order that the machines may be readily moved into and out of such places, the overall height of the machine is restricted and accordingly, the space available for the package columns is restricted.

In addition to the limitation as to the height of the columns, it is advantageous, if not necessary, that these machines be so constructed as to vend the products of several different manufacturers. In regard to cigarette vending machines, each column, or stack, is made up of one brand of cigarette. Accordingly, the supply of one brand of cigarette is limited to a small number of packages requiring the machine to be frequently serviced, and this adds materially to the cost of operating the machine.

In some of these vending machines, an attempt has been made to increase the number of packages by arranging them in two columns, one forwardly of the other. However, in such machines the packages ejected from the rear column are ejected under the weight of the packages in the forward column. This requires a greater effort on the part of the purchaser, if the machine is manually operated, or it requires more power if the machine is power operated, and such an arrangement increases the likelihood of the packages jamming and rendering the machine inoperative.

This invention has as an object a package vending machine embodying a structure whereby the packages are arranged in rows consisting of forward and rear columns, and package ejector mechanism operable to successively eject packages from the rear column without the ejected packages engaging, or coming in contact with the packages in the forward column. Upon exhaustion of the packages in the rear column, the ejector

2

mechanism successively ejects the packages from the forward column.

The invention has as a further object an ejector mechanism which is entirely automatically power operated and which embodies a structure whereby it is particularly rugged and durable, all whereby the machine has maximum reliability with minimum of maintenance.

The invention has as a further object an ejecting mechanism operable to selectively eject packages from one of several rows or stacks, and which consists of a single unit which can be quickly and conveniently removed, in its entirety, from the casing without the use of any tools, or interfering with the columns of packages, or other parts of the machine. This feature of the invention is of importance. In vending machines now in use, the package ejecting mechanism is of a relatively complicated nature and is built into the cabinet of the machine. Accordingly, when this mechanism becomes defective, it is necessary for the service man to disassemble the parts of the mechanism at its location and because these machines are usually located in crowded places, it is difficult for the service man to work on the machine. With my ejector mechanism, the entire mechanism is removable as a unit upon loosening two thumb screws and separating an electrical plug connection to the unit. Accordingly, if the unit becomes defective, it can be readily and quickly removed and replaced with a new unit, permitting the defective unit to be returned to the shop where it can be reconditioned under favorable shop conditions.

The invention consists in the novel features and in the combinations and constructions hereinafter set forth and claimed.

In describing this invention, reference is had to the accompanying drawings in which like characters designate corresponding parts in all the views.

Figure 1 is a front elevational view of a vending machine containing my invention.

Figure 2 is a vertical sectional view taken on line 2—2, Figure 1.

Figure 3 is a view taken on line 3—3, Figure 2.

Figure 4 is a view taken on line 4—4, Figure 3.

Figure 5 is an enlarged view of the package ejecting mechanism as shown in Figure 2.

Figure 6 is a view, similar to Figure 5, with the ejector mechanism in operation illustrating a package partially ejected from the rear column.

Figure 7 is a view, similar to Figures 5 and 6, illustrating the ejector mechanism at the end of

its forward stroke ejecting a package from the forward column.

Figure 8 is a schematic wiring diagram illustrating the electrical circuit embodied in the machine.

The invention consists generally of a suitable cabinet formed, or provided, with means for supporting a plurality of rows of packages, each row consisting of two columns, one arranged forwardly of the other, the columns being individually supported with the lowermost package in the forward column positioned in a plane above the lowermost package in the rear column. The package ejecting mechanism unit is arranged in the cabinet below the rows of packages and is operable to first engage and successively eject packages from the rear column of a selected row, the packages being ejected along a path below the forward column, whereby the ejected packages do not contact the packages in the forward column and upon exhaustion of the packages in the rear column, the ejecting mechanism thereupon successively ejects packages from the forward column.

The machine includes conventional coin operated mechanism for preliminarily conditioning the machine for the package vending operation. This operation, insofar as the purchaser is concerned, consists merely in pressing a switch button corresponding to the package, or kind of package, he desires to purchase. The package is ejected automatically by power operated means.

The cabinet 10 is formed of sheet metal, or the like, and is mounted upon a base 11 provided with floor engaging feet 12. The cabinet 10 is substantially U-shaped, with the open side forwardly, and to which is mounted an outer door 13 hinged along one side, as at 14. The door 13 is provided with a frame 15 in which are mounted a plurality of switch buttons 16, there being a button for each row of packages contained in the machine. The lower portion of the door 13 is provided with a frame 17 forming a discharge mouth or opening 18.

The cabinet 10 is detachably secured to the base 11 by thumb screws 20 extending through the top plate 21 of the base and threading into the bottom plate 22 of the cabinet. The cabinet is also formed with spaced apart upright partitions 24, 25, which are secured to the rear wall 26 of the cabinet. The forward edge of the upright 24 is secured to a flange 27 extending laterally from the side of the cabinet, see Figure 4. The lower edges of the uprights are bent inwardly forming flanges 28 welded, or otherwise secured to the bottom plate 22 of the cabinet.

The packages 29 are arranged in vertically extending rows, or stacks, by partition plates 30. The rear edges of these plates are bent to form flanges 31 secured to cross members 32 extending transversely of the cabinet and secured at their ends to the uprights 24, 25. The forward edges of the partitions 30 are bent to form package retaining flanges 33 for the forward columns. Angle pieces 35 are secured to the partitions 30 midway between the front and rear edges thereof, see Figure 4. These angle members 35 extend vertically and form guides for the rear ends of the packages in the forward column and for the forward ends of the packages in the rear column. The packages in the rear column 36 are supported by shelves in the form of angle members 40 secured to the lower ends of the partitions 30, see Figures 3 and 4, and extend forwardly under the forward column 41. The packages in the for-

ward column 41 are supported by similar shelves in the form of angle members 42. These however are positioned upwardly from the supporting members 40, whereby the lowermost package in the forward column 41 is positioned above the lowermost package in the rear column 36.

The package ejecting mechanism consists of a traylike frame member 45 mounted upon angle members 46 secured to the uprights 24, 25, the tray being inserted from the front of the machine on the angle members 46; and being detachably secured thereto by a pair of thumb screws 48. An operating shaft 49 is journaled at its ends in bearings 50, the shaft extending transversely of the tray 45 below the columns 36, 41. An arm 51 is secured at one end to the shaft 49 and is connected at its opposite end to a plunger 52 of a solenoid 53 by a link 54 and a yoke 55. The link 54 extends between the legs of the yoke 55 and is encircled by a helical compression spring 56 interposed between the bottom of the yoke and a collar 57 secured to the end of the link, whereby the solenoid is yieldingly connected to the arm 51. When the solenoid is energized, clockwise rotation of the shaft 49 is effected.

25 A plurality of carriers in the form of arms 58
are freely mounted upon the shaft 49. These
arms consist of a pair of side plates maintained
in spaced apart relation by shouldered pins. An
30 arm is positioned below each row of packages con-
sisting of the rear and forward columns 36, 41.
Package ejector members 59 and 60 are pivotally
mounted on the upper end of each of the arms
58. The ejector member 59 is pivoted to a rear-
wardly extending portion 62 on a pin 63. The
35 arm 60 is pivoted on a pin 64. The members 59,
60, are provided with counterweights 65, 66, re-
spectively. These counterweights serve to rotate
the members about their respective pivot pins in
40 a counter-clockwise direction, against stop pins
67, 68. When the member 59 engages its stop pin
67, the outer end of the member will engage the
rear end of the lowermost package in the rear
column 36 and slide the same along the annular
45 supporting members 40 to eject the package.
When the member 60 is in engagement with its
stop pin 68, see Figure 7, the outer end of the
member will engage the lowermost package in
the forward column 41 and, upon forward move-
ment of the arm 58, eject that package.

Means is provided for selectively connecting or coupling any one of the arms 58 to the shaft 49. A pin 10 is secured to the shaft 49 and extends upwardly therefrom between the side plates of each arm. The upper end of the pin is formed with a reduced neck portion 11 and a head portion 12.

The pins 70 are engaged by a latch member 75 pivotally mounted on pin 76 of each arm. The members 75 extend rearwardly from the arms, and the rearwardly extending portion 78 is weighted, as at 79, to effect a counter-clockwise movement of the member 75 about the pin 76. The forwardly extending portion of the member 75 is provided with a block 80 having a lip 81 to engage the neck 71 of the pin 70 when the member 75 is rotated in a clockwise direction, Figures 5, 6 and 7. Normally, the members 75 are positioned, as shown in Figure 5, and in this position forward movement of the pins 70, upon oscillation of the shaft 49 by the solenoid 53, does not transmit forward movement to the arms 58. The members 75 are selectively rotated clockwise by a solenoid 82 positioned below the rearwardly extending portion 78 of each of the

members 15. When energized, the plunger 83 of the solenoid moves upwardly engaging the tail portion 78 and moving the block 80 downwardly so that the lip 81 will be engaged by the neck of the pin 70 beneath the head 72, as shown in Figure 6. In this manner, the arm 58 is moved forwardly by the solenoid 53.

The solenoid 82 is energized by a switch 87 which is closed upon insertion of the proper coins in the coin control mechanism of the machine. As previously stated, the coin control mechanism may be of any conventional form, and is located on the upright 25, the mechanism being diagrammatically indicated by the rectangle 88, Figure 3. The frame 15 is provided with one or more coin receiving slots 89 arranged so that coins inserted in the slots pass into the coin control mechanism 88 and effect energization of the solenoid 82. Each of the solenoids 82 is connected in circuit through one of the push buttons 16, the push button switches 16 being connected in series with the coin operated switch 87. Accordingly, the purchaser may select the kind of package he desires by selecting the row in which such packages are arranged in the columns 36, 41, the selection being made by pressing the push button switch 16 corresponding to that row.

A control shaft 91 is also journaled in the tray 45 and extends parallel to the shaft 49 and to the rear of the arms 58 when the arms are in retracted position, see Figure 5. The shaft 91 is provided with a bracket 92 depending from the ends of the shaft and extending parallel therewith across the machine.

The members 15 are formed with depending arms 93. The bracket 92 is urged against the arms 93 by a spring 94, the arms being positioned against stop pins 95 carried by the respective arms 58. When the solenoid 82 is energized, and the plunger 83 accordingly elevated, clockwise movement of the member 15, and the arm 93 carried thereby, effects clockwise rotation of the shaft 91, moving the bracket carried thereby into engagement with a switch 96. Closing of the switch 96 effects energization of the solenoid 53.

Accordingly, when the proper coins are inserted in the coin slots 89 and one of the buttons 16 is pressed inwardly, the solenoid 82 is energized positioning the block 80 to be engaged by the corresponding pin 70 and thereupon energizing the solenoid 53, which effects clockwise rotation of the shaft 49, as previously explained, and this movement is imparted to the selected arm 58 through the pin 70 and the block 80, as shown in Figure 6. This forward movement of the arm 58 effects forward ejection of one of the packages 29 through a passage 97 into a package discharge chamber 98. The forward movement of the arms 58 under the influence of the solenoid 53 is rapid, and the momentum of the arm carries it forward after the plunger 52 reaches the bottom of its stroke. This forward movement brings the lip 81 of the block 80 out from under the head 72 of the pin 70, see Figure 7. The forward movement of the arm 58 is arrested by the pin 76 engaging the pin 70. The weight 79 effects counterclockwise movement of the member 15 about its pivot 76 to the position shown in Figure 5, whereupon the switch 96 is opened and the arm 58 is returned by the spring 110. Counterclockwise rotation of the shaft 49, Figures 5, 6 and 7, is effected by spring 99, Figure 4. The discharge chamber 98 is formed in an inner door construction consisting of a back plate

100 hinged at 101 to the flange 27, end plates 102, and a front plate 103. The discharge chamber 98 is positioned in register with the opening 18 in the outer door 13. The rear wall 100 and the bottom wall 105 of the discharge chamber are formed from sheet material extending transversely of the inner door structure and secured to the end plates 102 thereof. The bottom wall is of trough formation to receive the ejected packages indicated in dotted outline at 106, Figure 5. The discharge passage is formed by a baffle 107 forming a continuation of the package supporting members 40, and an inclined baffle 108 extending forwardly and downwardly from the rear wall 100 of the inner door structure and terminating remote from the front wall of the discharge chamber 98. A third baffle 109 extends inwardly and downwardly from the front wall of the discharge chamber below the lower end of the baffle 108. With this baffle arrangement, the packages are deposited in the bottom wall or trough 105 right side up, and the baffle arrangement prevents any tampering with the packages in the columns 36, 41. This package discharge arrangement minimizes the overall depth of the machine and prevents packages from being caught, or jammed, during ejection from the columns, or stacks. It will be understood that the baffles 107, 108, 109, extend transversely across the inner door structure.

As previously explained, the lowermost package in the forward columns 41 are positioned above the path traveled by the packages ejected from the rear column 36. The package ejector mechanism functions to first successively eject packages from the rear column and when that column has become exhausted, to successively eject packages from the forward column.

The arms 58 are moved to retracted position by tension springs 110, and during this rearward, or return, movement, the ejector member 59 engages the lowermost package in the rear column if there is one in the column, and is moved clockwise about its pivot 63, the member sliding under the package. When the arm has reached its full rearward stroke, the counterweight 65 swings the member 59 toward vertical position, as shown in Figure 5, and the next forward movement of that arm will eject the lowermost package, if any, in the rear column.

When the arm 58 has reached its rearward position, and if there is a package in the rear column, the rear side of the member 60 will engage the forward end of the package, and the member will be moved clockwise about its pivot 64. This movement is sufficient to lower the free end of the member below the lowermost package in the forward column, see Figure 5. Under these conditions, forward movement of the arm 58 will not effect ejection of a package from the forward column. If however, there is no package in the rear column, the counterweight 66 will swing the member 60 about its pivot, raising the upper end of the member in position to engage the lowermost package in the forward column, see Figure 7. This arrangement provides a very simple mechanism for successively ejecting the packages from both columns, and permits the guide flanges 33, 35, to be spaced apart to allow for regular cigarette packages, and also the longer packages, known in the trade as "king size."

The circuit for energizing the solenoids 53, 82, is illustrated diagrammatically in Figure 8. In this arrangement, the push button switches 16 are connected in series with each other and with the

coin operated switch 87. Insertion of the proper coin effects closing of contacts 120, 121, furnishing a hot lead to the movable element of the button switches 16. These elements are normally in engagement with contacts 122 to complete the series arrangement. When the contacts 120, 121, are closed and one of the push buttons 16 is pressed, the movable contact is moved into engagement with a contact 123 connected to one of the solenoids 82 through wire 124. The opposite side of the solenoid is connected to the common return 129, through wire 126. Accordingly, the solenoid 82, associated with the push button switch 16 actuated by the customer, is thus energized and effects closing of contacts in the associated switch 96. The switch 96 is connected to the hot side 128 of the supply through wire 129, and the opposite contacts of this switch is connected to one side of the solenoid 53, through conductor 130, the solenoid being connected to the common return 125 through wire 131. Accordingly, when any one of the solenoids 82 is energized, the switch 96 is closed, completing a circuit to the solenoid 53 for operating the package ejecting mechanism.

It will be understood that conventional coin switches include mechanism whereby the coin contacts of the switches are opened after the vending operation, and also usually include mechanism for returning the coins in the event the supply of packages in the machine has become exhausted. However, the coin mechanism may be of any such conventional design and forms no part of this invention.

It will be observed that the packages are ejected from the rear column without frictionally engaging the packages in the forward column, thus eliminating the possibility of the machine jamming when the forward column is completely filled with packages. This is an important feature because in many jurisdictions, in addition to the weight of the package, one or more pennies are inserted in the package for return change and these coins, plus the weight of the relatively high stack, exert considerable pressure on packages being ejected from the rear column in machines at present in use.

The machine is reloaded by opening the outer door 13 and the inner door structure carrying the discharge chamber and baffle structure, and when these doors are opened the ejecting mechanism, as a complete unit, can be removed by simply removing the two thumb screws 48.

What I claim is:

1. A package vending machine comprising a casing having means fixedly mounted therein for supporting forward and rear columns of packages, the lowermost package of the forward column being supported in elevated position relative to the lowermost package in the rear column, a carrier mounted in the casing and movable forwardly and rearwardly below said columns, a pair of package ejector members mounted on said carrier, means operable to yieldingly move said ejectors in engagement with the lowermost package in said columns respectively, one of said members being operable upon engagement with the lowermost package in the rear column and to eject the same upon forward movement of said carrier, the second ejector member being operable upon engagement with the lowermost package in the forward column and operable when so engaged and upon forward movement of said carrier to eject said lowermost package from the forward column, said second ejector member being main-

tained out of package engagement by the lowermost package in the rear column.

2. A package vending machine including a casing formed with means to separately support two columns of packages in tandem relation, an ejector carrier mounted in the casing and movable forwardly and rearwardly below said column, a package ejector pivotally mounted on said carrier, means operable to yieldingly move said ejector member to cause the free end thereof to engage the rear side of the lowermost package in the rear column, a second package ejector pivotally mounted on said carrier, means yieldingly urging said second ejector to cause the free end thereof to engage the rear side of the lowermost package in the forward column, actuating means operable to effect movement of said carrier forwardly and rearwardly below said columns, and said second ejector being maintained out of package engaging position by the lowermost package in the rear column.

3. A package vending machine comprising a casing having means fixedly mounted therein for supporting two columns of packages in a row with one column arranged forwardly of the other including a shelf for supporting the packages in the rear column and extending forwardly below the forward column, and a second shelf fixedly secured above the forward portion of said first shelf for supporting the packages in the forward column, a package ejecting mechanism arranged in the casing below said columns including a carrier mounted in the casing and movable forwardly and rearwardly below said columns, a package ejecting member mounted on said carrier for engagement with the lowermost package in the rear column upon forward movement of the carrier, a second package ejecting member mounted on the carrier for engagement with the lowermost package in said forward column upon forward movement of the carrier, said second package ejecting member being maintained out of package engaging position by the lowermost package in the rear column.

4. A package vending machine including a casing formed with means for receiving two columns of packages in a row, one arranged forwardly of the other, a shelf fixedly secured in the casing for supporting the packages in the rear column and extending forwardly below the forward column, a second shelf fixedly secured in the casing above the forward portion of said first shelf for supporting the packages in said forward column, a carrier mounted in the casing and movable forwardly and rearwardly below said columns, a package ejector member mounted on said carrier for engagement with the rear side of the lowermost package in the rear column upon forward movement of the carrier, a second package ejector mounted on said carrier for engagement with the rear side of the lowermost package in the forward column upon forward movement of said carrier, actuating means operable to effect movement of said carrier forwardly and rearwardly below the columns, and said second ejector member being maintained out of package engaging position by the lowermost package in the rear column.

5. A package vending machine including a casing formed with means to separately support two columns of packages, one carried forwardly of the other, package ejecting mechanism operable to successively eject packages first from said rear column and upon exhaustion of packages in said rear column to successively eject packages from said forward column, said mechanism including

a carrier mounted in the casing and movable forwardly and rearwardly below said columns, a package ejecting member mounted on said carrier for engagement with the lowermost package in said rear column upon forward movement of said carrier, a second package ejecting member mounted on the carrier for engagement with the lowermost package in said forward column upon forward movement of said carrier, said second package ejecting member being maintained out of package engagement by the lowermost package in the rear column.

6. A package vending machine including a casing having means for supporting two columns of packages, one arranged forwardly of the other, a carrier mounted in the casing below said columns and being movable forwardly and rearwardly thereof, a package ejector movably mounted on said carrier, means yieldingly moving said ejector to cause the same to engage the lowermost package in the rear column, a second ejector member movably mounted on said carrier, and means yieldingly moving said second ejector in position to engage the lowermost package of the forward column, said second ejector engaging the forward side of the lowermost package in the rear column upon rearward movement of the carrier and upon such engagement being prevented from engaging the lowermost package in said forward column, and actuating means operable to effect such forward and rearward movements of said carrier.

7. A vending machine comprising a casing, means for supporting two columns of packages, one arranged forwardly of the other, a package ejecting unit detachably mounted in the casing below said columns and including a frame, a shaft

journalled in the frame and extending transversely below said columns, an arm freely mounted on the shaft below said columns with the upper portion of said arm arranged in juxtaposition to the lower ends of said columns, coin controlled means mounted on the frame and being operable to couple said arm to said shaft, power actuated means mounted on the frame and operable to effect oscillation of said shaft to effect forward and rearward movement of said arm below said columns while the arm is coupled to the shaft, a package ejecting member for each column carried on the upper end of said arm and operable upon oscillation of the arm to engage and successively eject packages from said columns, said ejecting member for the forward column being maintained out of package engaging position by the lowermost package in the rear column.
